UNITED STATES PATENT OFFICE.

CHASE C. REED, OF TOLEDO, OHIO, ASSIGNOR TO THE R. & C. ENGINEERING COMPANY,
OF TOLEDO, OHIO, A CORPORATION OF OHIO.

PLOWING-MACHINE.

1,328,896.

Specification of Letters Patent. Patented Jan. 27, 1920.

Application filed November 25, 1916, Serial No. 133,339. Renewed June 13, 1919. Serial No. 304,086.

To all whom it may concern:

Be it known that I, CHASE C. REED, a citizen of the United States, residing at Toledo, in the county of Lucas and State of Ohio, have invented certain new and useful Improvements in Plowing-Machines, of which the following is a specification.

In my pending application Serial No. 130,424, filed November 9, 1916, I have described and claimed a plowing machine having a rapidly rotating plow or cutter mounted in a counterbalanced plow frame provided with gage wheels and arranged to be permitted a sidewise rocking movement as the gage wheels and plow are carried along, the plow being rotated through a sprocket chain engaging an equalizing device connecting the parts of a divided shaft, and the two members of such shaft being connected by sprocket chains engaging sprocket wheels on the ends of the shaft with sprocket wheels on the opposite ends of the cutter shaft. My present invention has the same general purpose as that described in my said previous application, and its main object is to provide a desirable machine, varying somewhat in construction and arrangement from the machine of my said prior application, and in which the motor which propels the machine and drives the rotary plow is arranged with the motor shaft extending longitudinally of the machine; a connection between a gear on the rear end of such shaft and a differential mechanism on a two-part shaft connected with the cutter permitting a rocking sidewise movement of the cutter frame and associated parts similar to that of the machine of my prior application. With the foregoing and incidental objects and advantages in view my invention consists in the construction, arrangement and organization of parts hereinafter described, the essential elements of which are more particularly pointed out in the appended claims.

In the drawings, Figure 1 is a side elevation of a plowing machine embodying my invention; Fig. 2 is a plan view of the same; Fig. 3 is a central vertical section of the differential mechanism and plow frame and plow at the rear end of the machine; Fig. 4 is a cross section on the line 4—4 of Fig. 3; Fig. 5 is a fragmentary longitudinal vertical section of a modified form of transmitting power to the differential mechanism,

and Fig. 6 a similar view of another modification.

The same reference characters indicate the same parts in all the figures of the drawing.

The frame 1 of my machine may be of any suitable construction and arrangement of frame members secured together to form a structure adapted to support the parts of the machine and mounted upon a pair of front 65 guide wheels 2, and a pair of caterpillars each consisting of a pair of wheels 3 mounted in a rocking truck 4 pivotally connected with the frame and engaged by the rolling platform 5. Near the center of the frame 1 70 is arranged the motor 6, the front end of the motor shaft 7 being arranged to be connected through manipulation of a clutch 8 with a change-speed transmission mechanism, which, as such devices are well known 75 and may indifferently be of one or another of various designs, need not be illustrated in detail and may be designated generally by the reference numeral 9 indicating the casing of such mechanism. The outer ends of 80 the members of a divided cross-shaft 10, the inner ends of which are connected by a differential mechanism arranged in co-operative relation with such change-speed mechanism, carry a pair of sprocket wheels 85 which by sprocket chains 12 are arranged to drive sprocket wheels secured to the rear wheels 3 of the caterpillar, in order to propel the machine.

Suitable steering mechanism, operated by 90 the hand wheel 13, is provided to direct the wheels 2 in unison and guide the machine.

The rear end of the motor shaft 7 is also arranged to be connected by a sliding clutch 14 with a driving shaft element 15 which is 95 in the present instance co-operatively connected with a change-speed transmission device, indicated generally by the reference numeral 16 adapted to rotate a second driving shaft element 17, which latter shaft 100 is rotatably and coaxially mounted in the trunnions 18 of a differential casing 19, said trunnions being journaled in bearings formed in downwardly-extending bearing block members 20^a formed integral with a 105 bracket plate or frame 20 extending across and secured to the frame of the machine at its rear end. The hollow axles or shaft supports 21 secured to opposite sides of the differential casing are equipped with antifric- 110

tion rollers 22, and in their rocking movements are guided and supported by slots 23 in depending side members 24 of the bracket plate or frame 20 before mentioned, so that 5 while the casing may rock upon the trunnions 18, the drag or pull of the plow frame hereinafter mentioned will be taken up by the opposite bracket members 24.

The rotating cutter or plow 25 of my machine is mounted to rotate in a U-shaped frame 26, the front end of this frame carrying on its cross-member 27 a pair of brackets 28 which rotatably engage the shaft supports or hollow axles 21 secured to the differential casing 19.

The rotary cutter or plow may suitably be of the same construction as in my prior application, and as in the machine there described the cutter frame is counterbalanced 20 by means of a weight 29 connected through block and tackle mechanism connected to a cross bar 30, and cables 31 connecting the ends of such cross bar with the sides of the cutter frame 26, and the depth of cut of the 25 plow is regulated by gage wheels 32 mounted on bearing plates 33 adjustably secured to the side members of the frame. A baffling shield 34 is pivotally mounted concentrically of the axis of the plow, and the front edge 30 of this shield is supported close to the surface of the ground by a roller 35 carried by the front of the shield.

The shaft 17 above mentioned carries, within the differential casing 19, a worm 36 arranged to engage the teeth of a gear wheel 37 of a differential or equalizing mechanism, which may be of any suitable construction, such, for instance, as those described in my prior application above mentioned, or 40 that illustrated in the accompanying drawings. As herein shown, the differential or equalizer comprises a series of rocking plates 38 carried by and pivotally mounted in openings in said gear wheel upon pivots extending radially across such openings, and a pair of hubs 39 mounted respectively upon squared portions of the inner ends of the members of the two-part axle or shaft 40 mounted in the shaft supports 21 and 45 formed with radial pivot blocks 41 arranged to engage end slots in the rocking plates 38. The extreme inner ends of the members of the shaft 40 form a pivotal support upon which the gear wheel 37 rotates. The outer 50 ends of the members of such shaft are provided with sprocket wheels 42 which by sprocket chains 43 are connected with sprocket wheels 44 on the opposite ends of the cutter shaft, completing the train of connections by which the cutter is rotated.

It will be understood that different variations and modifications of the structure above described are possible without departing from my invention. For instance, 60 as shown in Fig. 5, the driving shaft ele-

ment 17^a, corresponding to the part marked 17 in Fig. 4, may be equipped with a bevel pinion 45 arranged to mesh with the bevel gear 46 which forms part of a differential mechanism, the proportions of the differential casing 19^a and bearing block members 70 20^b, corresponding to the parts 19 and 20^a heretofore described, being modified accordingly.

A different modification is shown in Fig. 75 6 in which a sprocket chain 47 operatively connected to the motor is arranged to drive a sprocket wheel 48 mounted in bearings secured to the differential casing 19^b, a pinion 49 on the shaft of such wheel and in mesh 80 with a gear wheel 50 which forms part of a differential mechanism serving to communicate power to such mechanism;—it being understood that the construction and arrangement of parts associated with the modified forms of connection shown in said Figs. 5 and 6 may be substantially the same as illustrated in Figs. 1 to 4, inclusive, and hereinbefore described.

While in the above description and drawings I have described the differential casing as formed, with trunnions, it is obvious that if preferred the bearing or supporting member carried by the frame may be formed in the trunnions adapted to engage bearings 95 forming in the differential casing, and I therefore regard such reversal of elements as an equivalent construction falling within the scope of my invention and claims.

I claim:

1. In a plowing machine having a main frame and a motor mounted on said frame, a differential casing and connected opposite shaft supports, said casing being formed with trunnions journaled on a longitudinal axis in the frame of the machine, a divided shaft rotatably mounted in said supports, a cutter frame hinged to said differential casing structure on a transverse axis, a rotary cutter mounted in said frame, differential mechanism in said casing operatively connected with said motor and with the members of said divided shaft, and connections intermediate such members and said cutter for rotating the latter. 100

2. In a plowing machine having a main frame and a motor mounted on said frame, a differential casing and connected opposite shaft supports, said casing being pivotally mounted in said main frame on an axis running longitudinally of the machine, a cutter frame hinged on a transverse axis to said casing structure, a rotary cutter mounted in said frame, differential mechanism in said casing operatively connected 120 with said motor and with the members of said divided shaft, and connections intermediate such members and said cutter for rotating the latter. 125

3. In a plowing machine having a main 130

- frame and a motor mounted on said frame, a differential casing and connected opposite shaft supports, said casing being formed with trunnions journaled on a longitudinal axis in the frame of the machine, a divided shaft rotatably mounted in said supports, a cutter frame having side bearing members pivotally supported by said shaft supports, a rotary cutter mounted in said frame, differential mechanism in said casing operatively connected with said motor and with the members of said divided shaft, and connections intermediate such members and said cutter for rotating the latter.

4. In a plowing machine having a main frame and a motor mounted on said frame, a longitudinally disposed driving element arranged on said frame and operatively connected with said motor, a differential casing and connected opposite shaft supports mounted on trunnions journaled on a longitudinal axis in the frame of the machine, said driving element being mounted axially in said trunnions and being equipped with a gear, a divided shaft rotatably mounted in said supports, a cutter frame having opposite side bearing members pivotally supported by said shaft supports, a rotary cutter mounted in said frame, differential mechanism in said casing coöperating with said gear and with the members of said divided shaft, and connections intermediate such members and said cutter for rotating the latter.

5. In a plowing machine having a main frame and a motor mounted on said frame, a longitudinally disposed driving element arranged at the rear of said frame and operatively connected with said motor, a differential casing and connected opposite shaft supports mounted on trunnions journaled on a longitudinal axis in the frame of the machine, said driving element being mounted axially in said trunnions and being equipped with a worm, a divided shaft rotatably mounted in said supports, a cutter frame having opposite side bearing members pivotally supported by said shaft supports, a rotary cutter mounted in said frame, differential mechanism in said casing coöperating with said worm and with the members of said divided shaft, and connections intermediate such members and said cutter for rotating the latter.

6. In a plowing machine having a main frame and a motor mounted on said frame, a longitudinally disposed driving element arranged at the rear of said frame and operatively connected with said motor, a differential casing and connected opposite shaft supports mounted on trunnions journaled on a longitudinal axis in the frame of the machine, said driving element being mounted axially in said trunnions and being equipped with a worm and said differential casing be-

ing extended adjacent its trunnions to inclose said worm, a divided shaft rotatably mounted in said supports, a cutter frame having opposite side bearing members pivotally supported by said shaft supports, a rotary cutter mounted in said frame, differential mechanism in said casing coöperating with said worm and with the members of said divided shaft, and connections intermediate such members and said cutter for rotating the latter.

7. In a plowing machine having a main frame and a motor mounted on said frame, a differential casing and connected opposite shaft supports mounted on trunnions journaled on a longitudinal axis in the frame of the machine, a divided shaft rotatably mounted in said supports, differential mechanism in said casing operatively connected with said motor and with the members of said divided shaft, supporting bracket members secured to opposite sides of the machine frame formed with vertical front faces adapted to limit the movement of said supports near their ends, a cutter frame connected to said supports, and a cutter mounted in said frame and operatively connected with the members of said divided shaft.

8. In a plowing machine having a main frame and a motor mounted on said frame, a differential casing and connected opposite shaft supports mounted on trunnions journaled on a longitudinal axis in the frame of the machine, a divided shaft rotatably mounted in said supports, differential mechanism in said casing operatively connected with said motor and with the members of said divided shaft, a transverse member secured to the rear end of the main frame of the machine and formed with supporting side bracket members provided with vertical front faces adapted to limit the movement of said supports near their ends, a cutter frame connected to said supports and a cutter mounted in said frame and operatively connected with the members of said divided shaft.

9. In a plowing machine having a main frame and a motor mounted on said frame, a differential casing and connected opposite shaft supports mounted on trunnions journaled on a longitudinal axis in the frame of the machine, a divided shaft rotatably mounted in said supports, differential mechanism in said casing operatively connected with said motor and with the members of said divided shaft, sprocket wheels secured to the outer ends of the members of said divided shaft, depending bracket members secured to opposite sides of the main frame arranged inside and adjacent the planes of said sprocket wheels and formed with vertical slots receiving said supports near their ends, a cutter frame equipped with a rotatable cutter and having side bearing mem-

bers rotatably engaging said supports inside and adjacent the planes of said bracket members, and antifriction members arranged intermediate said bearing members and said 5 sprocket wheels, said sprocket wheels being arranged to drive said cutter.

10. In a plowing machine having a main frame and a motor mounted on said frame, a differential casing and connected opposite 10 shaft supports mounted on trunnions journaled on a longitudinal axis in the frame of the machine, a divided shaft rotatably mounted in said supports, differential mechanism in said casing operatively connected 15 with said motor and with the members of said divided shaft, sprocket wheels secured to the outer ends of the members of said divided shaft, depending bracket members secured to opposite sides of the main frame 20 arranged inside and adjacent the planes of said sprocket wheels and formed with vertical slots receiving said supports near their ends, a cutter frame equipped with a rotatable cutter and having side bearing members 25 rotatably engaging said supports inside and adjacent the planes of said bracket members, and antifriction members rotatably mounted upon the ends of said supports intermediate said bearing members 30 and said sprocket wheels, said sprocket wheels being arranged to drive said cutter.

11. In a plowing machine having a main frame and a motor mounted on said frame, a longitudinally disposed driving element 35 arranged at the rear of said frame and operatively connected with said motor, a differential casing and connected opposite shaft supports mounted on trunnions journaled on a longitudinal axis in the frame 40 of the machine, a divided shaft rotatably mounted in said supports, a differential mechanism operatively connected with said driving element and with the members of said divided shaft, bracket members secured to the opposite sides of the machine 45 frame and formed with vertical slots receiving said supports near their ends, a cutter frame connected to said supports, and a cutter mounted in said frame and operatively connected with the members of said 50 divided shaft.

12. In a plowing machine having a main frame and a motor mounted on said frame, a longitudinally-disposed driving element 55 arranged at the rear of said frame and operatively connected with said motor, a differential casing and connected opposite

shaft supports mounted on trunnions journaled on a longitudinal axis in the frame of the machine, a divided shaft rotatably 60 mounted in said supports, a differential mechanism operatively connected with said driving element and with the members of said divided shaft, a transverse member secured to the rear end of the main frame of 65 the machine and formed with side bracket members provided with vertical slots receiving said supports near their ends, a cutter frame connected to said supports, and a cutter mounted in said frame and operatively 70 connected with the members of said divided shaft.

13. In a plowing machine having a main frame and a motor mounted on said frame, a differential casing formed with trunnions 75 and connected opposite shaft supports, a divided shaft rotatably mounted in said supports, differential mechanism in said casing operatively connected with said motor and with the members of said divided shaft, a 80 transverse member secured to the rear end of the machine and formed with front and rear bearing block members receiving said trunnions of the casing and also formed with side bracket members having vertical 85 slots receiving said shaft supports, a cutter frame connected to said supports, and a cutter rotatably mounted in said frame and operatively connected with the members of 90 said divided shaft.

14. In a plowing machine having a main frame and a motor mounted on said frame, a longitudinally-disposed driving element arranged at the rear of said frame and operatively connected with said motor, a differential casing formed with trunnions adjacent its top and having connected opposite 95 shaft supports, said driving element being mounted axially in said trunnions, a divided shaft rotatably mounted in said supports, 100 the members of said divided shaft being rotated by said driving element, a transverse plate or frame secured to the rear end of the machine and formed with depending front and rear bearing block members receiving said trunnions of the casing and also 105 formed with depending side bracket members having vertical slots receiving said supports near their ends, a cutter frame connected to said supports, and a cutter rotatably mounted in said frame and operatively connected with the members of said 110 divided shaft.

CHASE C. REED.
